US00D891541S

(12) **United States Design Patent** (10) **Patent No.:** **US D891,541 S**
Lin (45) **Date of Patent:** **** Jul. 28, 2020**

(54) **HANDS AND FEET PULL EXERCISER**

(71) Applicants: **LONG TRAIN ENTERPRISE CO., LTD.**, Taichung (TW); **Richard Lin**, Taichung (TW)

(72) Inventor: **Richard Lin**, Taichung (TW)

(73) Assignee: **LONG TRAIN ENTERPRISE CO., LTD.**, Taichung (TW)

(**) Term: **15 Years**

(21) Appl. No.: **29/683,621**

(22) Filed: **Mar. 14, 2019**

(51) **LOC (12) Cl.** **21-02**

(52) **U.S. Cl.**

USPC **D21/692**

(58) **Field of Classification Search**

USPC D21/662, 682, 683, 684, 685, 692, 694; D24/189, 190, 212; D30/152, 153

CPC A63B 21/00043; A63B 21/02; B25G 1/102

(57) **CLAIM**

The ornamental design for a hands and feet pull exerciser, as shown and described.

DESCRIPTION

FIG. 1 is a perspective view of a hands and feet pull exerciser showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof; and,

FIG. 7 is a bottom plan view thereof.

The features presented in broken lines represent unclaimed portions of the hands and feet pull exerciser and form no part of the claimed design.

1 Claim, 7 Drawing Sheets
